OSCAR WOODWARD, OF NEW YORK, N. Y., ASSIGNOR TO YOST WRITING MACHINE COMPANY,
OF ILION, NEW YORK, A CORPORATION OF NEW YORK.

TYPE-WRITING MACHINE.

No. 893,828.

Specification of Letters Patent.

Patented July 21, 1908.

Application filed March 22, 1907. Serial No. 363,819.

To all whom it may concern:

Be it known that I, OSCAR WOODWARD, citizen of the United States, and resident of the borough of Manhattan, city of New York, in the county of New York and State of New York, have invented certain new and useful Improvements in Type-Writing Machines, of which the following is a specification.

My invention relates to platen clutch mechanism for effecting a connection and disconnection between the line spacing wheel and platen in order to produce fractional spacing when desired.

Heretofore great difficulty has been encountered in providing efficient fractional line spacing mechanism. It must be understood, in order to appreciate some of these difficulties, that the very finest adjustment is required between the line spacing wheel and the platen and that there must be absolutely no accidental displacement of the parts from this adjustment when once effected, as a thousandth of an inch displacement of a character out of a line of writing is quite perceptible in the printed matter. In devices where differential gearing was employed between the line spacing wheel and platen, there was almost invariably a "back lash" or lost motion in the gear connections which affected the results. Then again when frictional means were employed to connect the line spacing wheel and platen, considerable power, say thirteen pounds in some devices, was necessary to maintain the connection and this power must be overcome in releasing the device, rendering it difficult for the operator to actuate. Even with this power the friction devices were unreliable as the line spacing wheel was often accidentally displaced relatively to the platen when the line spacing lever was violently actuated, and the line spacing movement of the platen effected at a single operation. In devices which received a rotary

45 movement of a finger wheel or controlling piece and which required considerable power or pressure to effect an engagement or disengagement between the line spacing wheel and platen, an accidental displacement between the parts was liable to be effected without the operator observing it and the work was apt to be ruined. In devices which employ interlocking teeth to effect a clutching engagement between the line 55 spacing wheel and platen it is necessary to

have teeth of considerable size in order to bring about an effective interlocking engagement between the parts and a relative adjustment between the line spacing wheel and platen, and a fractional spacing of the platen for a distance less than the distance between two teeth of the engaging members cannot be effected and the usefulness of the device is restricted. The types will strike on predetermined fixed lines on the platen instead of using the entire surface of the platen. In any such constructions heretofore devised, the teeth of the engaging members restricted the adjustment or fractional spacing of the platen. Furthermore, in this class of devices the platen was often accidentally displaced from its adjusted position while an engagement was being effected and often the displacement occurred without the operator's knowledge. Thus, if the platen happens to be adjusted to a point where the crowns of the teeth on both engaging members come into contact during engagement of the parts, then the locking of the parts together will cause the platen to rotate until the teeth are brought into proper interlocking mesh and however slight the movement of the platen, it is sufficient to throw the work out of alignment and to render the written matter uneven and unsatisfactory.

From the foregoing it will be understood that in prior devices where positive or interlocking means were employed to connect the line spacing wheel and platen, the platen could not be adjusted to any point relatively to the line spacing wheel and connected to the wheel at the point of adjustment.

The object of my present invention is to overcome the above and other defects that have been encountered heretofore in fractional line spacing mechanism and to provide a fractional line spacing device which will be efficient in operation under all conditions of its use.

My invention is in the nature of an improvement on the structure disclosed in the application of Arthur W. Smith filed October 5th, 1905, Serial No. 281,406, the purpose of the present invention being more particularly to simplify the construction in order to expedite the manufacture and to render the structure more efficient.

To the above and other ends which will hereinafter appear, my invention consists in

the features of construction, arrangements of parts and combinations of devices to be hereinafter described and explained.

In the accompanying drawings, wherein like reference characters indicate corresponding parts in the various views, Figure 1 is a detail, central, longitudinal, sectional view of a platen and line spacing wheel showing my invention applied thereto. Fig. 2 is a like view of the same with parts broken away, the section being taken on a plane at right angles to that shown in Fig. 1. Fig. 3 is a detail front elevation looking towards the line spacing wheel and with the finger wheel sectioned away. Fig. 4 is a detail perspective view of a member to be hereinafter more fully described. Fig. 5 is a detail perspective view of one of the locking members. Fig. 6 is a like view of another of said locking members. Fig. 7 is a detail central sectional view of the cap or member secured to the right-hand end of the platen head. Fig. 8 is a detail perspective view of the line spacing wheel. Fig. 9 is a detail transverse sectional view showing the locking members, the section being taken on the line $x-x$ of Fig. 10 and looking in the direction of the arrow at said line. Fig. 10 is a fragmentary longitudinal sectional view similar to that shown in Fig. 1 but with the parts shown in the disengaged positions. Figs. 11 and 12 are views similar to Figs. 9 and 10 respectively but showing a different adjustment of the parts. Fig. 13 is a detail perspective view of the platen head at the right-hand end of the platen. Figs. 14 and 15 are detail longitudinal sectional views of one of the clutch carrying members and certain of the associated parts of the clutch mechanism. Figs. 16 and 17 are views in plan and side elevation respectively of some of the parts shown in Figs. 14 and 15.

The cylindrical platen 1 may be of any desired construction. The one shown is similar to that ordinarily employed in the Yost machine. It is preferably provided at the left-hand end with a platen head 2 which is secured to a hollow wooden core 3 of the platen by headed wood screws 4 which project through openings in the platen head and the stems of which take into the left-hand end of the core. An outwardly projecting sleeve 5 on the platen head 2 receives a spindle 6 which projects from a finger wheel 7, the spindle being connected to the platen head by a threaded connection 8 and a set screw 9. The stem of a headed bolt 10 projects through a central opening in the platen head 2 and its inner threaded end is received in a tapped opening in a nut or cap 11 threaded internally to receive and coöperate with the threaded end of a tubular bearing member 12 which may constitute a part of the platen head 13 shown in detail in Fig. 13. This right-hand platen head has a cylindrical

part 14 of a size to fit snugly in the hollow core 3 and also has a flange 15 which lies against the right-hand end of the core against which it is firmly held by the rod 10. Pins or lugs 16 project from the cylindrical portion 14 of the platen head into holes in the end of the platen core and prevent a relative rotation of the platen and platen head. The sheath or outer covering of the platen projects beyond the right-hand end of the core 3 and a metallic ring 17 is seated within said projecting sheath and constitutes a bearing for the flange 15 of the right-hand platen head, as shown in Fig. 2. This ring 17 is fixed to the platen and bears at its inner edge against the right-hand end of the core 3 and the outer edge of the ring constitutes a bearing for the inner side of the line spacing wheel 18. The line spacing wheel is in the nature of a ring such as that shown in Fig. 8 and the inner surface 19 thereof is received on a peripheral bearing edge 20 of a member 21 (shown in detail in Fig. 7) which is secured to the platen head by screws 22 (see Fig. 2), the stems of which pass through openings 23 in the flange-like portion of the member 21 and are received in tapped openings in the outer end of the platen head. A circumferential flange 24 is formed on the member 19 and constitutes a shoulder against which the outer side of the line spacing wheel 18 is adapted to bear, the member 21 thus constituting a bearing for the line spacing wheel to rotate upon and prevent a movement of the line spacing wheel longitudinally of the platen in one direction whereas the ring 17 constitutes a bearing that prevents the line spacing wheel from moving longitudinally of the platen in the opposite direction. The cap or member 21 being rigidly secured to the platen head by the screws 22 connects the parts and maintains the line spacing wheel in place on the platen head, though it allows the wheel to rotate thereon. The member 21 has a sleeve-like portion 25 which is tapped at 26 to receive a screw 27, the inner end of which is received in a hole in a hollow stem 28 seated at one end in the sleeve 22 so that the stem 28 is connected to the platen head to rotate therewith. The outer end of the hollow stem 28 is provided with a finger wheel 29 rigidly connected therewith.

A plunger 30 is received within the hollow stem 28 and is adapted to move longitudinally therein and the inner end of the plunger is provided with a stop pin 31 which extends on opposite sides of the plunger and is adapted to bear against the inner end of the hollow stem and prevent an endwise withdrawal of the plunger. The outer end of the plunger is provided with a finger piece or button 32 by which the plunger may be pushed inward. The line spacing wheel is provided with a series of circularly arranged crown teeth 33 which extend from the line

spacing wheel towards the opposite end of the platen into the annular space inclosed by the ring 17. The tips or crowns of these teeth are preferably beveled, whereas the 5 sides or body portions of the teeth are substantially parallel. The notches between the teeth 33 are adapted to receive a clutch tooth 34 projecting from a clutch member 35 shown in detail in Fig. 5. Said member has 10 a semi-circular part 36 that fits loosely over a semi-cylindrical part 37 of a carrier 38 (Figs. 16 and 17) that is loosely mounted in the tubular portion 12 of the right-hand platen head. The left-hand end part 39 of the carrier 15 is cylindrical and fits in the tube 12 with freedom to move longitudinally in said tube and this part of said carrier is recessed at 40 (Figs. 14 and 15) to receive a coiled expansion spring 41 which is adapted to bear at 20 one end against the bottom wall of the recess 40 in the carrier and depress the carrier toward the right. The right-hand end 37 of the carrier is, as heretofore stated, semi-cylindrical and its end engages the inner end 25 of the plunger 30 so that when the plunger or spindle is pressed inward the carrier is moved toward the left against the tension of the spring 41.

The right-hand platen head 13 has a transverse slot 42 formed therein, which slot is cut through the flange 15 to the cylindrical portion 14 and back a short distance into the tubular portion 12, the walls 43 and 44 (Fig. 13) of the slot being plane parallel surfaces, each 30 parallel to the axis of the platen. The semi-cylindrical part 36 of the member 35 fits loosely over the semi-cylindrical part 37 of the carrier 38 and inside of the tubular extension 12 so that the said member has both 35 a longitudinal and a turning movement. Said member 34 has radially projecting therefrom on opposite sides of the axis of the platen two wings 45 and 46 (see Figs. 5 and 16) and the tooth 34 is in the nature of an 40 extension of one of these wings 46. The wings project into the slot 42, the walls of which limit the turning movement of the member 35 in both directions. As shown 45 at 47 in Fig. 10 the core 3 of the platen is cut 50 away to admit the tooth 34. The wings 45-46 are each beveled at one side to form wedge surfaces 46^a, 45^a respectively (see Fig. 5). The motion of the member 35 longitudinally of the platen is derived from the carrier 38. The semi-cylindrical part 36 of the member 35 has formed in its right-hand edge a V-shaped notch 48 and is adapted to be engaged by a pin 49 projecting radially from the carrier 38 near the right-hand end thereof 55 when said carrier is moved inward by the spindle. 30. When said pin engages said notch it serves to swing the member 35 on its carrier. Said member is moved toward the right to press the tooth 34 into one of the 60 notches between the teeth 33 of the line spac-

ing wheel by spring pressure. Thus upon reference to Figs. 14, 15, 16 and 17 it will be seen that a sleeve 50 surrounds the carrier 38 at the cylindrical portion 39 thereof. This sleeve is provided with a semi-cylindrical extension 51 which projects towards the right and is adapted to engage at its edge with the inner edge of the member 35. A coiled expansion spring 52 surrounds the cylindrical portion 39 of the carrier and bears at one end 70 against a circumferential flange 53 at one end of the carrier and bears at its opposite end against the inner end of the cylindrical follower or member 50, so that the pressure of the spring 52 is exerted through the follower 75 50-51 against the member 35 to move it to the right. In order to guide the follower 50-51 in its longitudinal movement on the carrier and to prevent a turning movement of the follower on the carrier the follower may 80 be slotted as indicated at 54 in Fig. 16 to receive a guide pin 55 which projects from the semi-cylindrical portion 37 of the carrier so that the follower 50-51 is free to move longitudinally on the carrier but is fixed against 85 rotation independently thereof. It will be observed that the pins 49 and 55 are formed as the free ends of headed screws which, as shown in Figs. 14 and 15, are received in tapped openings in the carrier 38. The flattened portion 56 of the semi-circular part 37 of the carrier has a tapped opening therein 90 for co-operation with a headed screw 57 (see Fig. 14) having a shouldered portion 58 that constitutes a pivot for a locking or clutch member 59, shown in detail in Fig. 6. The pivot for this locking member extends at right angles to the axis of the platen as shown in Figs. 1 and 2 and the ends of the locking member extend on opposite sides of 95 its pivotal center and on opposite sides of the axis of the platen and are turned inwardly at right angles to the body portion thereof, as indicated at 60. The edge of each inwardly bent end is beveled or formed with a wedge-like surface 61, 62 and these beveled surfaces are adapted to co-operate with the beveled faces 46^a and 45^a respectively on the locking member 35. From an inspection of Figs. 9 and 11 it will be seen that the outer flattened face 63 of the locking member 59 cooperates with the wall 44 of the cut-out 42 in the right-hand platen head. The locking member 59, it will also be observed, is adapted to partake of the bodily movement of its 100 carrier 38 longitudinally of the platen and is likewise adapted to receive an independent turning movement on its pivot 57, the surface 63 sliding against the surface 44. The engagement of these two surfaces prevents 105 the member 59 and the carrier 38 from turning in the tube or tubular extension 12.

In the normal disposition of the parts shown in Figs. 1, 2 and 12, the line spacing wheel is positively locked to rotate with the 110 125 130

platen. Figs. 1, 9 and 10 show the position the parts assume if one of the notches between the teeth 33 of the line spacing wheel happens to be positioned centrally of the slot 42, while Figs. 11 and 12 show the position they assume if the notch happens to be to one side of the center of the slot 42. In either case in the normal position of the parts the carrier 38 and the clutch member 35 are both in their extreme right-hand positions, the tooth 34 being seated in the notch between two of the teeth 33 so that the locking member 35 is positively locked to the line spacing wheel. The locking member 59 has 15 its wedge surfaces 61 and 62 depressed into engagement with the wedge surfaces 46^a and 45^a respectively of the clutch member 35 by the spring 41. Said member 59 is thus wedged in between said member 35 on the 20 one end and the flattened face 44 of the slot 42 on the other, thus pressing the semicircular part 36 of the member 39 against the opposite side of the tube 12. The wedge 61 engaging the wedge 46^a prevents the platen 25 from turning toward the back of the machine and the wedge 62 engaging the wedge 45^a prevents rotation of the platen in the opposite direction. The platen head is thus positively locked to the member 35 which in turn 30 is positively locked to the line spacing wheel. In this position of the parts the pin 49 stands some little distance to the right of the notch 48 in the member 35. Should the operator desire to release the platen from the line spacing 35 wheel in order to effect a fractional line spacing movement of the platen, it is merely necessary to press the finger piece 32 to the left, thus moving the carrier 38 in a like direction.

40 The effect of the initial operation of the movement of the carrier 38 is to carry the locking member 59 out of interlocking and wedging engagement with the coöperating locking member 35. While this release is 45 being effected the spring 52 expands and holds the locking member 59 at the right-hand limit of its movement with the tooth 34 thereon engaged between two teeth 33 on the line spacing wheel. This engagement 50 between the tooth 34 and the teeth on the line spacing wheel continues until the carrier 38 has moved far enough to entirely disengage or throw the wedging or locking device 59 out of coöperation with the engaging 55 member or locking device 35. When this disengagement has been effected the pin 49 on the carrier 38 will come into engagement with the locking member 35 and a further movement of the carrier 38 to the left will 60 cause the locking member 35 to travel with it and the parts will be moved to the disengaged position shown in Fig. 10 with the tooth 34 out of engagement with the line spacing wheel. The locking member 59 at 65 this time will be disengaged from the mem-

ber 35. In this movement the pin 49 engaging the notch 48 has centered the member 39 so that its wings 45 and 46 are central of the slot 42 as shown in Figs. 9 and 10. The platen may then be rotated to any desired extent by either of its finger wheels 7 or 29 independently of the line spacing wheel. In the first part of the movements of the parts back to normal position the carrier 38 and the locking members 35 and 59 carried thereby travel in unison until the tooth 34 engages between teeth on the line spacing wheel. In this movement the member 35 is freed from the locking member 59 so that it is free to turn. The beveled tooth 34 therefore is 80 guided by the beveled teeth 33 and readily enters the notch between them, turning them slightly one way or the other, if necessary. When the tooth 34 is firmly seated in the space between two teeth 33, as indicated in 85 Fig. 12, then the movement of the locking member 35 to the right will be arrested, but a further continued movement of the carrier 38 takes place, and during the movement of the carrier 38 independently of the locking 90 member 35 the spring 52 is compressed, it being understood that the tension of the spring 41 is much greater than that of the spring 52. This continued movement of the carrier to the normal position will impart a 95 bodily movement to the locking member 59 which is carried thereby and will force the inclined wedges 61 and 62 thereof into a wedging engagement with the inclined faces 46^a and 45^a respectively on the locking member 100 35 and when the parts are in effected wedging and interlocking engagement the carrier will be arrested from further movement and the platen will be effectively and positively locked to the line spacing wheel at 105 the exact point where the platen was adjusted relatively to the wheel.

During the engaging movement of the locking member 35 hereinbefore described the tooth 34 thereof is brought into engagement with the teeth 33 on the line spacing wheel and the locking member 35 is free to receive a limited turning movement on its bearings and around the axial center of the platen. If during the engagement of these 110 parts the beveled crown of the tooth 34 should meet the beveled crown of a tooth 33 on the line spacing wheel the locking member 35 will be turned on its bearing around the axis of the platen until the tooth 34 finds its proper position between two of the teeth of the line spacing wheel, as shown in Fig. 8, it being understood that the line spacing wheel is at this time maintained against accidental displacement by a spring roller 115 120 125 130 135 140 145 150 155 160 165 170 175 180 185 190 195 200 205 210 215 220 225 230 235 240 245 250 255 260 265 270 ing movement, then the movement of the carrier 38 will, as heretofore pointed out, be continued. Any change in the angular position of the engaging member 35 effected during its engagement with the line spacing wheel will displace the wings 45 and 46 on the locking member so that they assume different angular positions in the cut-out portions 42 of the platen head. During the 10 bodily movement of the locking member 59 with the carrier one or the other of the inclined faces 61, 62 will be brought into engagement with its coöperating inclined face 46^a or 45^a before the other, and a further 15 bodily movement of the locking member 59 with its carrier effects a turning of the locking member 59 on its pivot so as to automatically swing the member 59 to a position where both of its wedge faces 61, 62 are in 20 engagement with the corresponding faces 46^a and 45^a respectively, so that it will properly coöperate with the locking member 35 in the angular position it has assumed during the engagement of this member of the line 25 spacing wheel. In Figs. 1, 9 and 10 of the drawings I have illustrated the locking member 35 as being centered within the opening 42 of the platen head, and in these circumstances the locking member 59 will move to 30 its locking position as shown in Fig. 1 without turning on its pivotal center, both engaging surfaces 61, 62 on the locking member 59 simultaneously engaging their respective coöperating wedge faces 46^a and 45^a on the 35 locking member 35. But in Figs. 11 and 12 said member 35 is displaced and the member 59 is correspondingly inclined.

From the foregoing it will be understood that the single tooth 34 is employed to interlock with and engage the large teeth 33 on the line spacing wheel and that during this engagement the locking member 35 may receive automatically a rotation around the longitudinal axis of the platen, and that during the engagement of the locking member 59 with the wedge surfaces on the locking member 35, said locking member 59 may automatically turn on its pivot to effect an adjustment of the locking member 59 and thus 50 the parts automatically regulate themselves or compensate for any shifting of the parts which may be effected by the engagement between the locking member 35 and the line spacing wheel, and none of the shifting thus 55 automatically effected displaces the platen relatively to the line space wheel so that the platen may be positively secured to the line space wheel at any point in the adjustment of the former relatively to the latter.

60 What I claim as new and desire to secure by Letters Patent, is:—

1. In a typewriting machine, the combination of a line spacing wheel, a platen that is adapted to be turned relatively to said wheel, and disengageable interlocking means for

positively connecting the platen and line spacing wheel at any point in the relative adjustment between the two, said means comprising two clutch members, a carrier, and a spring-pressed sliding follower surrounding 70 said carrier and bearing against one of said members.

2. In a typewriting machine, the combination of a line spacing wheel, a platen that is adapted to be turned relatively to said wheel, 75 and disengageable interlocking means for positively connecting the platen and line spacing wheel at any point in the relative adjustment between the two, said means comprising two disengageable clutch members, a 80 carrier for one of said clutch members, a spring surrounding said carrier and bearing against it at one end and operative on the clutch member co-acting with the carrier.

3. In a typewriting machine, the combination of a line spacing wheel, a platen that is adapted to be turned relatively to said wheel, and disengageable interlocking means for positively connecting the platen and line spacing wheel at any point in the relative adjustment between the two, said means comprising two clutch members, a carrier, a sleeve-like follower which surrounds said carrier and bears at one end against one of said clutch members, and a coiled expansion 95 spring which surrounds said carrier and bears at one end against the carrier and at the opposite end against the follower.

4. In a typewriting machine, the combination of a line spacing wheel, a platen that is 100 adapted to be turned relatively to said wheel, and disengageable interlocking means for positively connecting the platen and line spacing wheel at any point in the relative adjustment between the two, said means comprising two clutch members, a tubular bearing connected with the platen, a carrier for one of said members, the carrier being received in said bearing, a sleeve-like follower 105 which surrounds and is guided in its movement on said carrier and bears at one end against one of said clutch members, and a spring that surrounds said carrier and bears at one end against said follower and bears at its opposite end against the carrier. 110

5. In a typewriting machine, the combination of a line spacing wheel, a platen that is adapted to be turned relatively to said wheel, and disengageable interlocking means for positively connecting the platen and line 120 spacing wheel at any point in the relative adjustment between the two, said means comprising two clutch members, a tubular bearing connected with the platen, a carrier for one of said members, the carrier being received in said bearing, a sleeve-like follower which surrounds and is guided in its movement on said carrier and bears at one end against one of said clutch members, the follower being received within said tubular 125 130

- bearing, and a spring contained between the tubular bearing and said carrier and bearing at one end against the carrier and at the other end against the follower.
6. In a typewriting machine, the combination of a line spacing wheel, a platen that is adapted to be turned relatively to said wheel, and disengageable interlocking means for positively connecting the platen and line spacing wheel at any point in the relative adjustment between the two, said means comprising two clutch members, a carrier, a spring-pressed sliding follower surrounding said carrier and bearing against one of said members, a disconnectible cap, and a second spring interposed between said cap and carrier. 55
7. In a typewriting machine, the combination of a line spacing wheel, a platen that is adapted to be turned relatively to said wheel, and disengageable interlocking means for positively connecting the platen and line spacing wheel at any point in the relative adjustment between the two, said means comprising two clutch members, a carrier, a spring-pressed sliding follower surrounding said carrier and bearing against one of said members, a platen head having a tubular extension which forms a bearing for said carrier, a cup-like cap which surrounds the tubular extension at one end thereof, a connecting rod detachably connected to said cap, and a second spring interposed between said carrier and cap. 60
8. In a typewriting machine, the combination of a line spacing wheel, a platen that is adapted to be turned relatively to said wheel, and disengageable interlocking means for positively connecting the platen and line spacing wheel at any point in the relative adjustment between the two, said means comprising two disengageable clutch members, a carrier for one of said clutch members, a spring surrounding said carrier and bearing against it at one end and operative on the clutch member co-acting with the carrier, a platen head having an extension with a tubular bearing therein and in which said carrier is received, a cup-like cap which surrounds the end of the extension, a second spring in- 65
- terposed between said cap and carrier, a connecting rod threaded at one end for co-operation with a tapped opening in said cap, and a second platen head with which said rod is detachably connected at the other end. 70
9. In a typewriting machine, the combination of a line spacing wheel, a platen that is adapted to be turned relatively to said platen, and disengageable interlocking means for positively connecting the platen and line spacing wheel at any point in the relative adjustment between the two, said means comprising two disengageable clutch members, a carrier for one of said clutch members, a spring surrounding said carrier and bearing against it at one end and operative on the clutch member co-acting with the carrier, two platen heads one having a tubular bearing in which said carrier is received, a cap at one end of the tubular bearing, a second 75
- spring between said cap and carrier, a finder recess adjacent to a tapped opening in the cap, and a connecting rod between the other platen head and said cap, said rod having a threaded end guided to said guide opening in the cap by said finder recess. 80
10. In a typewriting machine, the combination of a line spacing wheel, a platen that is adapted to be turned relatively to said wheel, and disengageable interlocking means for positively connecting the platen and line spacing wheel at any point in the relative adjustment between the two, said means comprising a platen head having a bearing therein, two clutch members, a carrier for one of said clutch members, a follower, a spring between said follower and carrier, a pocket or recess in said carrier, and a second coiled expansion spring in said recess and bearing at one end against the bottom of said pocket 85 and at its opposite end against said bearing or a part carried thereby. 90
